[57] **CLAIM**

The ornamental design for a pillar cover for a truck, as shown and described.

DESCRIPTION

FIG. 1 is a perspective view of a pillar cover for a truck showing our new design;

FIG. 2 is a left side view thereof;

FIG. 3 is a front view thereof;

FIG. 4 is a right side view thereof;

FIG. 5 is a back view thereof;

FIG. 6 is a top view thereof;

FIG. 7 is a bottom view thereof;

FIG. 8 is a reduced perspective view of our design; and,

FIG. 9 is a reduced perspective view of a right side pillar cover for a truck showing another embodiment of our novel design which is identical to the embodiment of FIGS. 1-8 except it is mirror symmetrical.

The broken line showing of adjacent truck parts is only for showing the surrounding environment and is not part of the claimed design.

1 Claim, 4 Drawing Sheets
